FREQUENCY CONTROL APPARATUS

Louis A. Gebhard, Washington, D. C., assignor
to Wired Radio, Inc., New York, N. Y., a cor-
poration of Delaware

Original application January 8, 1930, Serial No.
419,401. Divided and this application October
15, 1932, Serial No. 638,013

12 Claims. (Cl. 171—327)

My invention relates broadly to frequency control apparatus and more particularly to a construction of frequency control apparatus which may be selectively adjusted for sustaining electrical oscillations at a number of predetermined frequencies.

This application is a division of my application Serial No. 419,401, filed January 8, 1930, for Temperature control apparatus for frequency control

10 devices.

One of the objects of my invention is to provide a construction of frequency control apparatus which includes a temperature controlled housing and a movable framework therein, the movable 15 framework carrying a multiplicity of electro-mechanical vibratile elements having switching means for selectively connecting any one of the electromechanical vibratile elements in an electrical circuit for sustaining high frequency oscillations therein.

Another object of my invention is to provide a construction of frequency control apparatus wherein a movable framework is journaled with respect to a stationary framework and is provided with a plurality of electromechanical vibratile elements disposed in a horizontal plane with contact members individual to each of the elements and adapted to coact with aligned contacts on the stationary framework for the selective connection of a particular electromechanical vibratile element in the circuit whose frequency is to be maintained.

A further object of my invention is to provide a construction of rotatable mounting frame for a 35 plurality of electromechanical vibratile elements with means for journaling the frame for rotation with a temperature controlled cabinet under control of an adjusting device operative from the exterior of the cabinet.

40 Other and further objects of my invention reside in the construction and arrangement of a multiplicity of electromechanical vibratile elements within a temperature controlled cabinet as set forth more fully in the specification hereinafter following by reference to the accompanying drawings, in which:

Figure 1 is a front view of the frequency control apparatus with the cabinet structure broken away to show the interior of the frequency control apparatus, partially in cross-section; Fig. 2 is a cross-sectional view taken through the temperature controlled cabinet on line 2—2 of Fig. 1 and showing the upper rotatable table which supports the casings containing the electromechanical vibratile elements in plan view; Fig. 3

is a fragmentary cross-sectional view through a portion of the temperature controlled cabinet and illustrating the manner in which the rotatable frame structure is removably connected with terminals within the cabinet structure; and Fig. 4 shows a detailed cross-sectional view of the structure of the side walls of the container for the frequency control apparatus.

In high frequency transmitters it is necessary to employ a system for maintaining the radiated energy at a substantially constant frequency. The exciter or master oscillator with which the apparatus of my invention is associated has the frequency thereof controlled by an electromechanical vibratile element. It is necessary to accurately control the temperature of the electro-mechanical vibratile element employed in order to maintain the selected frequency constant. Should a plurality of elements having different frequency characteristics be employed it is desirable to maintain all of the elements at substantially the same temperature. This usually necessitates providing a large space in the transmitter unit for the apparatus containing the temperature controlled elements.

A problem other than available space must be considered, namely, that the elements must be maintained at substantially uniform temperature otherwise the change from one element to another will not establish the necessary standard frequency. A third consideration is that the elements must be readily accessible for interchange of other elements and the elements must be adapted to be readily and easily connected to an external circuit and selectively chosen by the frequency characteristics of the external circuit.

I provide a set of horizontally extending supporting platforms which are carried by a vertically disposed shaft journaled centrally of a framework which is movable into and out of the cabinet structure. The platforms which are carried by the vertical shaft serve as supports for a multiplicity of casings, each of which enclose an electromechanical vibratile element. The casings are carried by the platforms in substantially radial alignment with the axes of the casings extending on substantially radial lines through the vertically disposed rotatable shaft. Contact clips are arranged adjacent the platforms and electrically insulated from each other to engage the terminals on the casings. The contact clips are so arranged that the casings are individually removable from the platforms to permit substitution of another casing enclosing an electromechanical vibratile element. Contact blades are

- provided in electrical connection with the contact clips carried by the platforms. These platforms coact with stationary contacts supported adjacent the rotatable platforms. In order that the proper electromechanical vibratile element 5 may be selected and electrically connected in an oscillation circuit, the contact blades projecting from the platforms alternate in their arrangement, that is, the contact blades on one platform 10 are offset with respect to the contact blades on an adjacent platform so that the selected electromechanical vibratile element is connected into the control circuit for each angular adjustment 15 of the rotatable platforms.
- Fig. 1 of the accompanying drawings shows a front view of the temperature control apparatus of my invention. A portion of the front of container 1 is shown cut away showing discs 10 and 10a, upper plate 15 and lower plate 16 in section. 20 Shaft 11 rests in bearings 13 and 14 provided in plate members 16 and 15 respectively. Like reference characters are employed throughout the drawings. A resilient arm member 21 is carried by collar 21b mounted on shaft 11. Arm 21 carries a semispherical member 21a which engages with detents located in the surface of ring member 22 and as shaft 11 rotates the detents serve as stops to maintain the electrical connection to the ring 22. Ring 22 is secured in position with 25 respect to member 15 by means of screws 22a by which an electrical connection to screw 22a may be provided in any suitable manner. Bar 8 may be secured to plate members 15 and 16 by means of angle members 9 and screws 8a. Bevel gears 25 interconnect with shaft 11 and with shaft 26. Shaft 26 extends at right angles to shaft 11 and protrudes through the front side of container 1. Shaft 26 may be entirely of suitable insulating material the purpose of which is to 30 prevent any pronounced transfer of heat between the inside and outside of container 1, or the shaft 26 may be broken by a suitable insulating coupling at the position where the shaft 26 passes through the walls of the cabinet contacts 23 and 24 in engagement with brushes 6. Discs 10 and 10a 35 are shown in section comprising a carrier for elements 2 and 2a, respectively. As shown, elements 2 and 2a are piezo electric crystals contained in individual holders which are removable. Clips 19 and 20 connect to the two contact lugs carried by the holders and establish electrical connection to the crystal elements. A brush 21c mounted on collar 21b extends radially opposite arm 21 to form a movable electrical contact with ring 22. Part of the surface of ring 22 contains the detents for receiving the member 21a while the remainder of the surface of the ring 22 is employed for providing contact with brush 21c. 40 While piezo electric crystal elements have been referred to, it is obvious that other elements such as magnetostriction rods may be employed. The necessity for maintaining the temperature of magnetostriction rods at a constant value, is as important as maintaining constant the temperature 45 of piezo electric elements. From the outside of container 1 the selection of different elements may be controlled by dial and knob 52 which is carried on shaft 26. Dial and knob 52 also indicates the element which is connected to the external circuit at each adjustment. With a permanent selection of elements as in a transmitting system operating on certain frequencies, dial 52 50 may be calibrated in kilocycles. Door 37 is shown in section. The edges of door 37 are recessed as shown in Fig. 1 at 36. Hinges 38 are provided

at the left of the door and a latch is provided at the right. This latch is not shown in the accompanying drawings but is of suitable design to force door 37 to form a very close fit with the recessed edges of the front wall of container 1. 80 Where the hinged door carries a heater element, there are provided suitable flexible connectors 60-61 between the heating element in the cabinet walls and the terminals 62-63 of the heating element carried by the hinged door for completing the electrical circuits. The outermost layer 27 of suitable insulating material is here shown in section, exposing layer 28 upon which the heater element is wound. The heater wire is wound in notches 28a disposed in the opposite ends of layer 28 and extends across the layer as illustrated. The top and bottom turns of the heater wire are secured in the notches 28a as shown at 29a, while the principal portions of the heater wire are disposed on the inner side of layer 28. Between layer 28 and the distributing layers of metal, previously referred to, a layer 29 of suitable heat conducting and electrical insulating material is provided. 90 Thermometer 40 is shown in section; a clamping member 42 securing the body of the thermometer in the proper position and the graduated temperature scale or upstanding portion 41 in a vertical position. The body of thermometer 40 extends through the front panel of container 1. 100 The upstanding portion 41 is calibrated and indicates the temperature inside the container. The mercury type thermostat 32, also previously referred to, is shown in side elevation. Distributing layers 31 and 31a of aluminum or other suitable metal are shown separated thereby providing an opening for the body of the thermostat. The control portion or stem extends through bushing 32b which is threaded into the insulating layers on the top side of container 1. Lower plate member 16 forming part of the unit framework is elevated from the bottom of container 1 by members 35. Screws 51 are provided to secure the heat insulating layer 27 to the other layers of the container. Screws 50 extend from layer 110 26 through to layer 34. The heater element is wound in notches 28a provided in layer 28. Screw holes 50a are shown through which the screws 51 pass when the outermost panel 27 is in place. By removing the four screws indicated, access is 115 had to the heater element for adjustment, repair or replacement. This feature is very desirable since it is often times necessary to adjust the length of the heater wire employed to provide equality of temperature in all sides of the container 1. A and B indicate binding posts which are employed in a modification of my invention. The heater element is separated near the binding posts A and B to avoid any short circuit of the heater elements. Dial 52 is shown carried on 120 shaft 26 at the front of the container. By means of dial 52 selection of the desired piezo electric element is made possible as aforementioned in connection with Fig. 1. The upstanding stem 41 of mercury type thermometer 40 is positioned with 125 respect to the front of container 1 by means of clamping members 42. This thermometer indicates the temperature of the inside of the container. Mercury type thermostat 32 illustrated in Figs. 1, 2 and 4 is secured by bushing 32b in the 130 wall of the cabinet structure. The thermostat socket is constructed by causing a bulge in the distributing layers 31 and 31a which receives the thermostat as has been described heretofore. 135 Fig. 2 is a top plan view in part section show-

ing the apparatus of my invention. The electro-mechanical vibratile elements 2 are mounted on a framework contained within container 1. A stationary contact member 6 is carried by a contact arm 7 which is secured to bar 8 by means of screw 7a. Bar 8 is supported by an angle 9. Elements 2 have associated contact lugs which engage with clips 19 and 20. Clips 20 are positioned on an annular metallic member 12 by screws 12a. Member 12 is in turn supported by shaft 11 which is of metal. Elements 2 rest upon a disc 10 which may be of insulating material. Near the periphery of disc 10 contact clips 19 are provided for retaining the other contact lug of elements 2. The electrical connection to elements 2 is therefore provided by connecting to contacts 23 and shaft 11. Disc 10 may be of metal, in which case clips 19 and contacts 23 would be supported by but suitably insulated from disc 10. Disc 10 is supported from shaft 11 by member 12 and is movable therewith. A second disc 10a is also carried by shaft 11, which disc is similar to disc 10 and carries a plurality of mechanically vibratile elements 2a. Disc 10a and one of the elements 2a is shown in the broken section of disc 10. Shaft 11 is supported in suitable bearings shown in Fig. 1 and is rotated by shaft 26 under control of knob 52 to which dial 52a is attached. Shaft 26 has a bevel gear 25 thereon intermeshing with a similar gear on shaft 11. The revolving framework carrying the elements 2 and 2a and the stationary contact assembly are all positioned with respect to a framework comprising a lower plate member 16 and upper plate member 15. Rods 17 extend between the lower plate member 16, and the upper plate member 15. Inasmuch as Fig. 2 is a section through the cabinet below the upper plate member 15, only the lower plate member 16 is shown although the arrangement of the plate members is clearly shown in Fig. 1.

Container 1 is cube shaped which is satisfactory for most purposes. The ideal shape would be spherical. However, manufacture of this design is not wholly practicable. The nearest approach is the cubical shaped construction employed in accordance with my invention. All six sides of the cube shaped container are made up of laminated sheets of material. The outermost layer 27 is of suitable insulating material. The second layer 28 is of insulating material upon which the heater wire 29a is wound. Next is a thin layer of mica 29b or other electrical insulating but heat conducting material. This layer is employed primarily to electrically insulate the heater from the next two layers 31 and 31a which are of metal such as aluminum, and which act as heat distributing layers. A filler layer 29 is provided which substantially surrounds the thin layer of mica 29b and heater wire 29a, thus equalizing the thickness of the several layers at any position through the walls. Layer 29 may be made of any suitable heat insulating material. Next is a layer of asbestos 33 or similar material 65 which is adjacent to a layer of copper 33a. Any desired number of alternate layers of asbestos 33 and copper 33a may be provided between the distributing layers 31, 31a and the inside layer 34 of the container which may be of aluminum or other suitable material for lining the interior of the container. The distributing layers 31, 31a are bulged as shown at 32a providing an opening for a mercury type thermostat 32. To permit access to the mechanically vibratile elements, a door 37 is provided in the front side of container

1. The opening for the door is of special design, the edges being stepped as shown at 36. By recessing the edges in this manner a very efficient heat insulating joint can be had. Leakage of air to the inside of the compartment or vice versa is almost entirely eliminated. Thermometer 40 is provided to indicate the temperature of the inside of the compartment. Thermometer 40 has an upturned portion 41 at right angles to body 40. This permits visual indication of the temperature scale. Thermometer 40 extends through an opening in the front of container 1 and is positioned adjacent the front by means of clamping screws 42.

Fig. 3 shows further details of the temperature controlled apparatus of my invention. The illustration shows a sectional view taken through the side wall of the container showing particularly the top and right side of the container. It is sometimes desired to remove the entire rotatable frame-work which carries the mechanically vibratile elements. As heretofore mentioned, the elements associated with the adjusting mechanism and contact members are mounted on a framework consisting of an upper and lower plate member and supported by rod members extending vertically as shown in Figs. 1 and 2. The upper plate member 15 is here shown carrying contact member 43 supported by upstanding members 55. Contact member 43 consists of two laminated spring metal arms. Positioned on the top of container 1 there is provided an insulating member 45 which carries contact member 44. Contact members 43 and 44 may be properly called plug and jack respectively. Contact member 44 is electrically connected to the metallic body 46 of binding post 8 by connector 44a. An insulating body 46a surrounds the metallic body 46, thereby electrically insulating the same from the metallic distributing layers. An electrical connection is established between terminal 43a of contact 43 to the stationary contacts or supporting bar 8 shown in Fig. 1. By referring to Fig. 1 it may be seen how such connection can be provided by connection to screw 8a. An arrangement similar to that shown in Fig. 3 is also provided for establishing electrical connection to the other side of the mechanically vibratile element, which as heretofore described is provided for metallic annular shaped member 22. In the latter connecting arrangement a contact member similar to contact 43 is electrically connected to annular shaped ring 22 or to the mounting screw 22a which holds the same to upper plate member 15. This contact arrangement is provided so that it is possible, by removing the front wall of container 1, the entire framework carrying the vibratile elements may be removed from the housing 1, thereby permitting access to the unit in its entirety for repair, replacement and the like.

Fig. 4 shows a section of the wall of container 1 and illustrates the method of mounting different members on the container. The layers as previously mentioned are insulating layers 27 and 28, heat conducting and electrical insulating layer 29, heat distributing layers 31 and 31a, alternate layers of asbestos or the like and suitable metal such as copper 33 and 33a respectively and the inside lining 34 of suitable metal such as aluminum. The essential feature shown in this illustration is that no screws extend through the entire wall of the container. Such screws if extended through all of the layers would offer a path of relatively high temperature conductivity. For this reason the screws are arranged in

a manner somewhat as shown, wherein screw 51 extends part way through the wall, namely through the layers 27, 28, 29 and threaded into the distributing layers 31, 31a. The member 58 is secured by a separate screw 50 which extends through layers 28, 29, 31, 31a, 33, 33a and 34. A countersunk screw as shown may be employed in the latter instance. Where it is not desired to mount a member 58 on the inside of the container, screw 50 may be threaded into the innermost layer 34. By fastening the several layers together in this manner, any apparatus desired may be mounted directly upon metallic layer 34. The screws may be distributed on the several walls of container 1 as desired depending upon the rigidity sought.

By referring to Figs. 1 and 2, an understanding of the operation and the advantageous features will appear. The elements 2 on the upper platform 10 and the elements 2a on the lower platform 10a are arranged to be connected to the external circuit in alternate order. This may be accomplished by having the elements 2a positioned offset as shown in Fig. 2 or the equivalent, the contact members offset in like manner.

The stationary contact members 6 carried by bar 8 may be suitably arranged to connect to elements 2 and 2a in alternate order when elements 2 and 2a are positioned immediately under each other instead of the offset positioning as shown in Fig. 2. Any number of discs similar to discs 10 and 10a may be employed arranged one over the other as shown. The elements or connection to the elements may be from first one disc and then the next in successive order which may be effected by placing the rotating contacts to the elements in echelonic formation with respect to the different discs or the stationary contacts may be arranged in such a manner if it is desired to place the elements in line one over the other on the respective discs. The discs should be of sufficient number or proportionally spaced on shaft 11 to occupy the area of a cube as nearly as possible. Thus if four discs of diameter d are employed the vertical dimension occupied by all the discs should be d and the separation between the discs divided accordingly.

The various layers constituting the sides of container 1 are interleaved at the corners as shown in Fig. 1 of the accompanying drawings. The heater elements in the six sides are connected in series to permit the same current to pass through each element. Minor irregularities in the heating can be controlled by adjusting the length of the wire constituting the heater element in each of the sides. The container 1 in its entirety is mounted on the front panel of the radio transmitter or apparatus.

A door should be provided in the front panel of the transmitter corresponding to the position of door 37 by means of which access to the mechanically vibratile elements may be had. A suitable window should also be provided in the front panel to permit sighting thermometer 41. Thermostat 32 is located adjacent the heater element provided in container 1 and connected with a suitable source of electrical energy for controlling the current to the heater. The framework supporting the rotating platforms is secured to the front panel and may be drawn out horizontally in the process of disassembly which disengages the contacts 44 and 43, permitting withdrawal of the equipment in order that repairs or mechanical adjustment may be made to the mechanism. Screws 80 are provided through the laminations

28, 29, 31, 31a, 33, 33a and 34 for binding the front group of layers to enable the front section to be removed or inserted as a unit. Access to any one of the crystals is readily obtained by rotating the platforms to bring the desired crystal to a position at the front of the cabinet from which it may be inserted or removed.

The apparatus of my invention may be mounted with respect to a panel of a radio transmitter with a suitable window cut in the panel to permit sighting the scale of the thermometer 41 there-through.

Shaft 26 projects through the front of panel 64, the knob 52 and dial being secured to the end of shaft 26. The calibrations on the dial are registered with a calibration on panel 64 to enable the apparatus to be shifted to the desired frequency.

Many modifications of my invention are possible and it is to be understood that the embodiments of my invention are not to be restricted by the foregoing specification or by the accompanying drawings but that changes may be made within the scope of the appended claims without departing from the spirit of my invention.

What I claim as new and desire to secure by Letters Patent of the United States is as follows:

1. Frequency control apparatus comprising in combination a container of substantially cube contour, a supporting frame positioned in said container, a rotary framework journaled in said supporting frame, said rotary framework comprising a plurality of horizontally disposed disks spacially arranged on a vertically positioned shaft and a plurality of electromechanically vibratile elements carried by said disks, contact members on said disks connected with said elements, contact members on said supporting frame, said first mentioned contact members being adapted to be selectively engaged with the second mentioned contact members carried by said supporting frame.

2. Frequency control apparatus comprising in combination a container, a stationary framework mounted in said container, a movable framework supported by said stationary framework, said movable framework carrying a plurality of electromechanically vibratile elements disposed in a horizontal plane, contact members individual to each of said elements, sets of stationary contacts mounted on said stationary framework, the contact members on said movable framework being adapted to be selectively connected with the stationary contacts carried by said stationary framework.

3. Frequency control apparatus for signaling systems comprising in combination a container having enclosed therein a rotatable framework consisting of a plurality of platforms arranged one over the other in separate horizontal planes, a plurality of electromechanically vibratile elements mounted on each of said platforms, contact members carried by said platforms and individually connected with each of said elements, and sets of stationary contacts within said container in alignment with the contacts on said platforms.

4. Frequency control apparatus for signaling systems comprising in combination a container having enclosed therein a rotatable framework consisting of a plurality of platforms arranged one over the other in horizontal planes, a plurality of electromechanically vibratile elements carried by each of said platforms, contact members carried by said platforms and individually

- connected with said elements on said platforms, said contact members alternating in position one with respect to another on the respective platforms, sets of stationary contacts within said container in alignment with the contacts on said platforms whereby connection of said elements to an external circuit is completed alternately through an element carried by different platforms. 5
- 10 5. Frequency control apparatus comprising a cabinet structure, a frame mounted within said cabinet structure, a vertically disposed shaft member journaled in said frame, a horizontally disposed platform carried by said shaft member, 80
- 15 a multiplicity of frequency control devices carried by said platform, a contact member carried by said platform individual to each of said frequency control devices, contact members carried by said frame structure, and means projecting 85
- 20 through said cabinet structure for rotating said shaft and imparting movement to said platform for switching said frequency control devices selectively into engagement with the contact members on said frame structure in step by step operations. 90
- 25 6. Frequency control apparatus comprising a cabinet structure, a frame mounted within said cabinet structure, a vertically disposed shaft member journaled in said frame, a horizontally disposed platform carried by said shaft member, 95
- 30 a multiplicity of frequency control devices carried by said platform, a contact member carried by said platform individual to each of said frequency control devices, contact members carried 100
- 35 by said frame structure, a gear on said shaft, a control shaft projecting through said cabinet structure normal to the aforesaid shaft, a gearing connection between said shafts interiorly of said cabinet structure whereby rotation of said control shaft exteriorly of said cabinet structure imparts corresponding movement to said platform interiorly of said cabinet structure for selectively connecting or disconnecting contacts individual to each of said frequency control devices with the 105 contacts on said frame structure. 110
- 40 7. Frequency control apparatus comprising a supporting container, terminal clips mounted within said container, a movable framework slideable into and removable from said container, contacts carried by said framework adapted to 115
- 45 electrically connect with the terminal clips within said container, a rotatable support journaled with respect to said framework, a plurality of electromechanical vibratile elements mounted on said rotatable support and having contact blades adapted to register with contact members on said framework, and means operative from the exterior of said housing for rotating said rotatable support to a position where said electromechanical vibratile element is selectively connected with a control circuit. 120
- 50 8. Frequency control apparatus comprising a cabinet structure, terminal clips in said cabinet structure, a frame insertable into and removable from said cabinet structure, terminals carried by said frame adapted to electrically connect with 125
- 55 130
- 60 135
- 65 140
- 70 145
- 75 150
- the terminal clips within said cabinet structure, a rotatable shaft journaled in said frame, platforms carried by said rotatable shaft in spaced relation, electromechanical vibratile elements supported on said platforms, switch blades individual to each of said electromechanical vibratile elements, contacts carried by said frame, and means operative from the exterior of said cabinet structure for angularly shifting said platforms for selectively connecting a predetermined electromechanical vibratile element with a control circuit through the contact clips on said frame. 90
9. Frequency control apparatus comprising a cabinet structure, a support within said cabinet structure, a vertically extending shaft journaled in said support, a plurality of platforms spaced one above another carried by said shaft, sets of contact clips disposed radially on each of said platforms, casings each enclosing an electromechanical vibratile element supported on said platforms and having terminals electrically connected with said contact clips, switch blades individual to certain of said contact clips and movable in the path of contact clips carried by said support, and means exterior of said cabinet for angularly shifting said shaft for selectively connecting a predetermined electromechanical vibratile element with the contact clips on said support. 100
10. In a device of the class described, a rotary mounting, a plurality of removable crystal holding units supported by said mounting and symmetrically disposed thereon, each of said crystal holding units having a pair of contact lugs, said mounting having a plurality of contact clips engageable with said lugs, a housing for said mounting, said housing having at least one pair of electrical binding posts for connecting one of said crystal holding units into a given circuit, and stationary connectors electrically connected 110 with said binding posts for connecting said contact clips selectively, whereby, upon rotation of said mounting, any desired crystal holding unit may be introduced into said given circuit. 115
11. Frequency control apparatus comprising a plurality of mechanically vibratile elements, an individual container for each element having contact lugs exterior thereof for connecting said element into a given circuit, a rotatable framework for supporting said containers in symmetrical arrangement about the axis thereof, a housing in which said rotatable framework is carried, said housing having binding posts extending through a wall thereof, and means for selectively connecting said binding posts with the contact lugs 125 of any desired individual container, said means being operable in accordance with the rotation of said framework. 130
12. A device in accordance with claim 11 in which said rotatable framework is provided with a plurality of platforms having contact clips secured thereto and adapted for engagement with the contact lugs of said individual containers whereby each of said containers is held in position on said platforms. 135

LOUIS A. GEBHARD.
